CLAIM

The ornamental design for a knife handle, as shown and described.

DESCRIPTION

FIG. 1 is a rear left side perspective of a knife handle, the right-side being a mirror image, showing my new design. FIG. 2. is a left-side view of the knife handle thereof, the right-side being a mirror image.

FIG. 3 is a top view thereof.

FIG. 4 is a bottom view thereof.

FIG. 5 is an enlarged rear view thereof; and,

FIG. 6 is an enlarged front view thereof.

The broken lines shown in FIGS. 1 through 6 illustrate environmental structure that form no part of the claimed design. The broken lines shown on the knife handle in FIGS. 1, 2 and 5 illustrate portions of the knife handle that form no part of the claimed design.

1 Claim, 4 Drawing Sheets(56)
